UNITED STATES PATENT OFFICE

90,712

DESIGN FOR A DISPLAY STAND

Percival Goodman, New York, N. Y., assignor to
The McKay Company, Pittsburgh, Pa., a corporation of Pennsylvania

Application July 27, 1933. Serial No. 48,846

Term of patent 7 years

To whom it may concern:

Be it known that I, PERCIVAL GOODMAN, a citizen of the United States, residing at New York city in the county of New York, State of New York, have invented a new, original, and ornamental Design for a Display Stand, of which the following is a specification, reference being had to the accompanying drawing, forming a part hereof,

Figure 1 is a plan view of the stand embodying my new design, and Fig. 2 is a perspective view of the stand.

I claim:

The ornamental design for a display stand, as shown.

PERCIVAL GOODMAN.
